UNITED STATES PATENT OFFICE.

THOMAS J. LAING, OF CLARKSBURG, WEST VIRGINIA.

BRAKE BEAM.

Application filed May 7, 1926. Serial No. 107,440.

This invention relates to brake beams, embodying among other characteristics a reversible member adapted for connection with brake rods leading in opposite directions.

5 An object of the invention contemplates a tension member for holding braking elements upon the ends of a supporting beam.

A further object of the invention comprehends locking means carried by the braking 10 elements for associating brake shoes therewith.

More specifically stated the reversible member is adapted for detachable engagement with a supporting beam in order that 15 brake rods may be readily associated therewith, thereby obviating the usual necessity of reversing and altering the portion of the entire beam.

With the above and other objects in view, 20 the invention further includes the following novel features and details of construction, to be hereinafter more fully described, illustrated in the accompanying drawing and pointed out in the appended claim.

25 In the drawings:

Figure 1 is an elevation of the invention.

Figure 2 is a sectional view taken on line 2-2 of Figure 1.

30 Figure 3 is a top plan view of the reversible member as set up for use.

Figure 4 is a sectional view taken on line 4-4 of Figure 1.

Figure 5 is a sectional view taken on line 5-5 of Figure 2.

35 Figure 6 is a sectional view taken on line 6-6 through the reversible member of Figure 3 of the drawing.

Referring to the drawing in detail, where- 40 in like characters of reference denote corre- sponding parts, the reference character 10 indicates the frame of a truck, not shown,

45 Hanger members 11 are carried thereby at appropriate points and at spaced intervals thereon and which provide embossed pockets

45 12. Pivoted links 13 have their upper ends positioned within the enclosures defined by the pockets and mounted upon pivot pins 14 extending to the adjacent side walls thereof.

50 Brake heads 14' are provided with aper- tured flange portions 15 adjacent their ends and between which the lower ends of the pivoted hangers 13 are connected to suspend the brake heads. Forward faces at the brake heads are provided with spaced

aligned apertured ears 16 registering with 55 the portions as defined by forwardly and obliquely disposed fingers 17, the purpose of which will be readily apparent.

Brake shoes 18 provided with apertured lug members 19 are adapted for interposition 60 between the ears 16 of the brake heads 14 and adapted for the ultimate reception of locking keys 20 extending through the aper- tured portions thereof.

The off set upper ends 21 of the keys are 65 guided between the uppermost of the fingers 17 and abut the upper portions of the brake heads 14' to prevent such keys from falling through the apertured portions of the aligned ears and lugs respectively.

The corresponding inner sides of the brake heads 14' are provided with triangular shaped pockets or sockets 22 within which 70 the extremities of an angular beam 23 are received.

A reversible fulcrum 24 is provided with reduced and pointed end portions 25. Said 75 ends are cutout as indicated at 26 in Figure 4 of the drawing.

Either of the ends 25 is adapted to be 80 fitted within one side of the angle beam 23. Said beam receives within the cutout por- tions 26 thereof trunnions 27 carried by a cleviis 28 also having its end portions lapped upon the opposed sides of the particular end 85 portion 25 to receive a fastening element 29 therethrough.

A tension member 30 has its end portions 90 extending through the pockets or sockets 22 in the brake heads 14' while the inter- mediate portion of its length is passed through a V-shaped opening 31 arranged 95 in the free end of the reversible divider member 24. Said tension member is broken at an appropriate point in its length and has connected to the broken ends thereof a turn- buckle 32 which when tightened will force the ends of the angle beam 23 within the sockets or pockets 22 whereby the brake 100 shoes 18 carried and locked upon the brake head 14' may be arranged and sustained in alignment with wheels, not shown, upon which said shoes are applied.

Said fulcrum member is twisted upon it- 105 self between the reduced and pointed end portions 25 thereof at any desired pitch or inclination. An elongated longitudinally disposed slide portion 33 provided in the

member 24 communicates with openings 34 in the adjacent side walls of the member.

In the use and operation of the present invention a shaft, such as indicated at 35 is passed through the free end of the member 24 and extends in a vertically disposed position with relation thereto. The upper end of the said shaft forms a loop 36 within which a spring, not shown, is fitted to properly support and position the entire structure in proper position for use. A brake lever, not shown, is passed and fulcrumed within the slide portion 33 of the reversible fulcrum 24 which has connected to the opposite ends thereof a brake lever and fulcrum respectively.

It is to be noted that the reduced and pointed ends 25 of the reversible fulcrum 24 are the same. Said end may be selectively positioned and secured to the angle beam 23 and by virtue of the pitch of the brake lever, not shown, is fulcrumed within the slide portion 33 also arranged at an inclination in order that a brake rod leading in different directions may be readily fitted and connected to such brake lever upon the reverse attachment of the appropriate end of the member. In other words the opposite ends of the reversible fulcrum may be reversed in the instance of connecting a brake

rod with a brake lever fulcrumed and carried thereby.

Obviously the operation of a brake rod in conjunction with the fulcrum brake lever will operate to equalize the draft of the 35

brake shoes 18 upon traction wheels, not shown.

The invention is susceptible of various

changes in its form, proportions and minor

details of construction, and the right is here-

in reserved to make such changes as prop-

erly fall within the scope of the appended

claim.

Having thus described my invention what

is claimed is:

A device for use upon brake beams comprising a fulcrum terminating to provide pointed end portions, said fulcrum being twisted in different directions and provided with an elongated longitudinally disposed slotted portion, said ends being provided with cut-out portions and adapted for engagement with said beam, a clevis carried by the beam pivotally connected with the adjacent end of the fulcrum, and trunnions 55 carried by the clevis projected through the beam within the cut-out portions of the fulcrum to prevent displacement of the latter.

In testimony whereof I affix my signature.

THOMAS J. LAING.
